UNITED STATES PATENT OFFICE.

LOUIS D. FARNSWORTH, OF PALO ALTO, AND MAX J. BARTELL, OF SAN FRANCISCO,
CALIFORNIA.

ELECTRIC FURNACE.

No. 924,603.

Specification of Letters Patent.

Patented June 8, 1909.

Application filed April 3, 1908. Serial No. 424,882.

To all whom it may concern:

Be it known that we, LOUIS D. FARN-
SWORTH, of Palo Alto, county of Santa Clara,
State of California, and MAX J. BARTELL, of
the city and county of San Francisco, State
of California, both citizens of United States,
have invented new and useful Improvements
in Electric Furnaces, of which the following
is a specification.

10 Our invention relates to electric furnaces,
and especially to furnaces for smelting iron
or other metalliferous ores.

One object of the invention is to provide a
furnace in which the disposition of the elec-
15 trodes and the passage of the electric current
are entirely independent of the distance be-
tween the electrodes; thereby enabling furna-
ces of any desired size to be economically
constructed, and to be constructed without
20 having to take into consideration the accu-
rate adjustments of the electrodes relative to
one another.

Another object is to construct a furnace in
which there is a vertical distribution of the
25 current in the crucible. This vertical dis-
tribution makes it possible to regulate the
electric current by changing the height of the
metal level.

Another object is to provide a means
30 whereby the amount or strength of the elec-
tric current may be maintained the same
when the furnace is discharging its molten
metal, or, in other words, is being tapped, as
when the tap is closed.

35 Another object is to provide means where-
by the molten slag itself is adapted to vary
the resistance in the circuit, and therefore
afford the medium for regulating the cur-
rent. And our object generally is to pro-
40 vide an electric furnace of large capacity,
which is simple and cheap of construction,
wherein the electrodes are permanently built
into the furnace, and in which furnace there
is no requirement of a variable voltage, or of
45 movable electrodes.

The invention consists of the parts and the
construction and combination of parts as
hereinafter more fully described and claimed,
having reference to the accompanying draw-
50 ings, in which—

Figure 1 is a horizontal section on line
X—X, Fig. 2. Fig. 2 is a vertical section on
line Y—Y, Fig. 1. Fig. 3 is a vertical sec-
tion on line Z—Z, Fig. 1.

55 In the embodiment of our invention A rep-

resents the crucible of a furnace having a
suitable brick lining. Suitably disposed in
the reduction chamber of the furnace, and
overhanging the crucible, are two or more
electrodes 2, preferably built permanently
60 into the furnace, with the electrodes ar-
ranged radially of the crucible and at a suit-
able distance above the bottom of the latter.
The electrodes are disposed horizontally and
project a short distance into the furnace, and
65 are preferably arranged for a three-phase
system. The electrodes are disposed at ap-
proximately 120 degrees apart, and the ends
of the electrodes are cut wedge-shaped, so
that each electrode presents a parallel end
70 edge or surface to each of the other elec-
trodes, and results in a more even distribu-
tion of the current through the material to
be treated. By thus cutting the ends of the
electrodes so that the ends are equal dis-
75 tances apart, the space between the three
electrodes is substantially Y-shaped. Suit-
able electrical connections, not necessary
here to be shown, are made between these
electrodes and any appropriate source of
80 electrical supply. The electrical current,
however, instead of passing straight across
from one electrode to the other, is designed
to pass down through the slag layer in the
furnace, which is represented at 3, to the
85 body of molten metal 4, and thence across
through the metal to the opposite electrode.
This is what we term the vertical distribution
of current in the crucible.

90 The quantity of current or the strength of
the current passing through the body of
material undergoing treatment is regulated
by increasing or diminishing the depth of the
slag, which is adapted during operations to
95 be in contact with the under side of the elec-
trodes. Thus, by employing suitable means
to increase the volume of metal 4 in the cru-
cible, the distance between the metal and the
under side of the electrodes will be dimin-
100 ished, and the resistance offered by the slag
to the passage of the electric current will cor-
respondingly be diminished. Conversely,
by lessening the depth of the metal body 4,
the depth of the slag would be increased,
105 and correspondingly the resistance to the
electric current would be increased. Any
suitable means may be employed to effect
this variation of the depth in slag and metal.
As here shown, we provide a forehearth or
110 supplemental chamber 5 of suitable area,

having suitable connections 6 at the bottom, with the bottom of the crucible; through which connections 6 the molten metal may freely flow from the supplemental chamber 5 to the crucible, and vice versa. The front of the supplemental chamber 5 has a tap 7 through which the molten metal may be drawn off from time to time, this tap being normally closed in a manner usual in the art.

- 10 A plunger 8 of carbon or other suitable material, and designed to practically fill the supplemental chamber operates in the supplemental chamber for the purpose of raising and lowering the level of the molten metal 15 in the crucible; the operation of the plunger being effected by any suitable means, as the stem 9. By pushing down on the plunger a certain quantity of the metal in the supplemental chamber is displaced into the crucible, raising the metal level therein, and decreasing the thickness of the slag between the electrodes and the top of the metal. Correspondingly, by raising the plunger, the amount of metal in the crucible is decreased. 25 The molten slag may be drawn off from time to time through a suitable aperture, as 10.

The electrodes are suitably insulated, and on their under sides they are cut away where they pass through the walls of the furnace, so 30 that there will be no tendency for the current to follow down through the walls of the furnace to the metal, and thereby destroy the walls. The electrodes overhang the crucible so that contact could be made between 35 the slag and the under side of all the electrodes.

In operation, the crucible is first filled with charcoal or other suitable heating and conducting material, and the electric current 40 turned on. In a short while the charcoal is converted into a bed of glowing coals, whereupon the charge to be treated is dumped in, and after a time a body of metal, as 4, accumulates in the bottom of the crucible. The 45 current from one electrode passes down through the slag and the metal in the bottom of the crucible, and thence travels across the bottom of the crucible through the metal and up through the slag to the other electrodes. 50 By the lowering or raising of the plunger in the supplemental chamber, the distance through the body of slag between the electrodes and metal can be varied, thus varying the resistance in the circuit, and affording a 55 means of regulating the current.

By suitably manipulating the plunger 8 when drawing off metal from the furnace, it is possible to maintain a constant thickness of slag between the under side of the electrodes and the top of the metal, and thereby avoid a variation in the resistance or the amount of current.

For practical and obvious reasons, the distance apart of the electrodes is generally 60 in excess of twice the depth of the body of

slag between the under side of the electrodes and the body of metal 4.

Having thus described our invention, what we claim and desire to secure by Letters Patent is—

1. In an electric furnace, the combination with the crucible thereof, of electrodes overhanging the crucible, said electrodes having inner ends normally of wedge-shape and said electrodes and crucible being arranged so 75 that the current between the electrodes will pass downwardly through a body of slag, and thence across through the molten metal in the crucible, and a supplemental chamber at one side of the crucible in open connection 80 with the latter, and into which chamber the molten metal will freely flow.

2. In an electric furnace, the combination with the crucible thereof, of electrodes fixed within the furnace, and overhanging the crucible, a chamber at one side of the crucible and connecting with the bottom thereof, and means operating within said chamber to displace the molten metal therein and raise the level of the molten metal in the crucible. 90

3. In an electric furnace, the combination with the crucible thereof, of electrodes overhanging the crucible and permanently built thereinto, and having their inner ends normally of wedge shape, said electrodes and crucible so arranged that the current between the electrodes will pass downwardly through a body of slag, and thence across through the molten metal in the crucible, and means for varying the depth of the slag between the electrodes and metal, said last-named means including a displacing chamber. 95

4. In an electric furnace, the combination with a crucible, of three electrodes arranged therein horizontally and overhanging the crucible, the ends of said electrodes being cut wedge-shaped, so that the space between the ends of the electrodes is substantially Y-shaped, said electrodes and crucible so constructed that the electric current in passing from one electrode to the other will distribute vertically through the slag, and horizontally through the molten metal in the crucible. 105

5. In an electric furnace, the combination with a crucible, of three electrodes arranged therein horizontally and overhanging the crucible, the ends of said electrodes being cut wedge-shaped, so that the space between the ends of the electrodes is substantially Y-shaped, said electrodes and crucible so constructed that the electric current in passing from one electrode to the other will distribute vertically through the slag, and horizontally through the molten metal in the crucible, and means for varying the vertical traverse of the current through the slag. 115

6. In an electric furnace, the combination of a reduction chamber, electrical reduction 120

means therein, a supplemental chamber connected with the reduction chamber, and a displacing member in the supplemental chamber for varying the amount of metal in the reduction chamber, and thereby varying the current passing through the reduction chamber.

7. An electrical furnace having a reduction chamber and having a supplemental chamber, said chambers having fluid connections whereby molten metal may flow from one to the other, electrodes in the reduction chamber, said electrodes arranged so that the electric current distributes vertically through the slag and horizontally through the molten metal in the reduction chamber, and a displacing member operating in the supplemental chamber for varying the amount of slag between the electrodes and the metal in the reduction chamber.

8. An electrical furnace having a reduction chamber and having a supplemental chamber, said chambers having fluid connections whereby molten metal may flow from one to the other, electrodes in the reduction chamber, said electrodes arranged so that the electric current distributes vertically through the slag and horizontally through the molten metal in the reduction

chamber, and a plunger operating in the supplemental chamber for varying the amount of slag between the electrodes and the metal in the reduction chamber.

9. An electric furnace having a reduction chamber, electrodes in the reduction chamber, said reduction chamber having a discharge for the molten metal, and means operative through the molten metal in the reduction chamber whereby the molten metal may be drawn off without affecting the electrical current.

10. An electric furnace having a main reduction chamber and a supplemental chamber connected together at the bottom, electrodes in the reduction chamber, and a plunger in the supplemental chamber operative to raise and lower the body of metal in the reduction chamber toward and from the electrodes.

In testimony whereof we have hereunto set our hands in presence of two subscribing witnesses.
